UNITED STATES PATENT OFFICE.

WILLIAM H. NOELTING, OF EVANSVILLE, INDIANA, ASSIGNOR TO FAULTLESS CASTER COMPANY, OF EVANSVILLE, INDIANA, A CORPORATION.

SELF-RETAINING CASTER SOCKET FOR ANGLE-IRON LEGS.

Application filed May 26, 1923. Serial No. 641,589.

To all whom it may concern:

Be it known that I, WILLIAM H. NOELTING, a citizen of the United States, and a resident of Evansville, county of Vanderburgh, and State of Indiana, have invented a certain new and useful Self-Retaining Caster Socket for Angle-Iron Legs; and I hereby declare that the following is a full, clear, and exact description thereof, reference being had to the accompanying drawings, in which like numerals refer to like parts.

This invention relates to a caster bracket socket for angle iron legs which are usually found upon washing machines and the like.

The chief object of the invention is to construct a bracket which will clampingly engage the lower end of an angle iron leg to be secured thereto and which will support said leg upon a caster by means of a socket arrangement which may be detachable or integral with the bracket.

The several features of the invention are as follows:

25 A metal bracket having parallel and oppositely turned clamping lateral edges for engagement with the angle iron longitudinal edges.

30 A wedging engagement associated with each angle iron edge.

A lateral support or ledge and preferably under the end of each angle iron side.

An upturned flange to form a socket with the supporting ledge above noted.

35 A support for yieldingly supporting and retaining the caster in the bracket.

An arrangement for limiting the inward movement of the caster.

In several instances a clamping engagement with the caster or caster socket.

40 In several instances a triangular base plate having a caster stem receiving opening therein which is positioned so as to secure a predetermined relationship between the caster stem or socket supporting the same and the walls of the angle iron leg.

45 The full nature of this invention will be understood from the accompanying drawing and the following description and claims.

50 In the drawings Fig. 1 is a longitudinal sectional view along an angle iron leg and the caster bracket socket showing the same upon the former and supporting a caster stem thereon. Fig. 2 is a top plan view of

the caster bracket socket with the pintle of the caster construction associated therewith, and the angle iron shown in transverse section. Fig. 3 is a side elevational view of an angle iron leg, the caster bracket socket 60 and a portion of the caster associated therewith.

Fig. 4 is a phantom view of a caster stem and the angle iron leg and a side elevational view of a modified form of bracket in position thereon. Fig. 5 is a top plan view of the same with the angle iron leg in section. Fig. 6 is a front view of the bracket and a phantom view of the caster stem and angle iron, the angle iron and the caster 70 stem being shown by dotted lines.

Fig. 7 is a view similar to Fig. 4 but of a modified form of the invention. Fig. 8 is a view similar to Fig. 5 but of the modification shown in Fig. 7. Fig. 9 is a view 75 similar to Fig. 6 but of the modification shown in Figs. 7 and 8.

Fig. 10 is a view similar to Fig. 1 and of another modified form of the invention. Fig. 11 is a view similar to Figs. 2, 5 and 8 80 and of the modification shown in Fig. 10. Fig. 12 is a view similar to Figs. 6 and 9 and of the modification shown in Figs. 10 and 11.

Fig. 13 is a view similar to Figs. 4 and 85 7 and of another modified form of the invention. Fig. 14 is a view similar to Figs. 5, 8 and 11 and of the modification shown in Fig. 13. Fig. 15 is a view similar to Figs. 6, 9 and 12 and of another modified 90 form of the invention. Fig. 16 is a view similar to Fig. 7 and of another form of the invention. Fig. 17 is a view similar to Figs. 5, 8, 11 and 14 and of the modification shown in Fig. 16. Fig. 18 is a view 95 similar to Figs. 6, 9, 12 and 15 and of the modification shown in Figs. 16 and 17. Fig. 19 is a top plan view of a modified form of the invention and is very similar to that shown in Figs. 7 to 9 inclusive. Fig. 20 100 is a top plan view of a modified form of the invention and is very similar to that shown in Figs. 13 to 15 inclusive. Fig. 21 is a top plan view of a modified form of the invention and is very similar to that shown in 105 Figs. 16 to 18 inclusive.

The invention relates to a bracket adapted to be secured upon an angle iron leg and yieldingly retain a caster which, under load through the bracket, supports the leg. This 110

invention is another type, but serves the same purpose as the caster bracket socket shown in the prior Patent No. 1,383,773.

In Figs. 1, 2 and 3 one form of the invention is illustrated, and this form of the invention is shown mounted upon an angle iron having the sides 20 with longitudinal edges 21 and ends 22 and the central angle or edge 23. The caster may be of the usual type and herein such a caster is illustrated as comprising a yoke or base 24 which supports a pintle or stem 25 herein shown as having a curved head 26 and a reduced neck portion 27. A flange 28 assists in securing the yoke to the stem, but any form of caster might be utilized except as will be hereinafter noted.

Extending in a plane beneath the end 22 is a base 30 which has forwardly projecting portions 33 which constitute ledges adapted to support the end of the leg. These ledges may, or may not, terminate in a plane parallel to the outer face 20 of the leg side, but herein such ledge is shown extended at an angle to the same as at 34, and this angle may form a gradually tapering groove if desired, which loses its taper when the leg is received thereby, or the flange 34 may extend upwardly in parallel relation to the side 20. Thus a wedging or clamping engagement with said side may be secured. The base 30 is substantially triangular in shape and two sides of said triangle are provided with forwardly projecting ledges 33 and the up-turned retaining flanges 34. The third side or base of the triangle is provided with an up-turned back 35 which extends across the angle of the angle iron and each end of the back 35 is extended at 36 to lie parallel to the longitudinal edge 21 of the leg and at right angles thereto. The extension 36 is further extended at 37 and this in turn at 38, each being at an angle to each other to form a clamping groove, which groove is adapted to receive the longitudinal edge 21 of the angle iron. As shown clearly in Figs. 1 and 3, and indicated by the numerals 39 in said figure it is noted that the grooves are inclined towards each other as they approach the base, thereby insuring a wedging or clamping action when the bracket is inserted on the end of the angle iron, or pressure or weight is applied thereto. All of these several features are common to substantially all forms of the invention except that shown in Figs. 10, 11 and 12.

The back 35 is extended outwardly and forwardly as at 40 to form a cap or top adapted to engage the top of the head 26 of the stem 25 and limit the inward movement of the stem. This overhead extension 40 is turned downwardly and inwardly as indicated at 41 to provide a tongue for engaging the neck 27 of the stem 25 to yieldingly

retain the caster stem in the socket. Thus, a frictional yielding engagement is formed by the forward extension 40 and the tongue portion 41 to retain the stem in the socket. The base 30 is apertured as at 42 and a flange 43 defines said opening and is formed from the metal constituting the opening. The back 35, as shown clearly in Fig. 1, is herein shown adapted to lie substantially parallel to and have a linear engagement 75 with the stem 25, and the tongue 41 maintains the stem in upright relation against said back.

In Figs. 4, 5 and 6 a slightly modified form of the invention is illustrated and herein similar parts of the bracket are similarly numbered except that the numbers are increased by 100 in value. In addition to the substantially similar construction, this modification of the invention includes a pair of forwardly projecting curved fingers 144. These fingers are formed by slitting the back 35 at 145 and then turning the projecting portions forwardly and in a curved relation so as to form a cylindrical, or if the 85 90 95 100 105 110 115 120 tionship is secured by means of the back portion 235 and the engagement of the socket 250 upon the inner walls of the sides 20 of the angle iron or adjacent the angle 5 23 of the angle iron.

In Figs. 10, 11 and 12 a modified form of the invention is illustrated. In this form of the invention similar parts of the bracket are indicated by numerals of the 300 series.

10 Herein the lateral supporting ledges are indicated by the numeral 333, the up-turned flanges associated therewith by 334. The inside of the groove construction engaging the longitudinal edge 21, is indicated by the 15 numeral 336. The base thereof is indicated by the numeral 337 and the front face thereof by the numeral 338. The wedging engagement is indicated by the numeral 339. Herein the back, indicated 20 generally by the basic numeral 35 in the preceding figures, is not positioned so that it extends straight across the angle formed by the angle iron, but the sides 336 are extended parallel to the sides 20 of the angle iron at 356, and these extensions extend adjacent each other until they very nearly meet at the angle 23 of the angle iron. Thereupon they are turned back, as shown 25 by the dotted lines at 357, to form a tubular, 30 and herein cylindrical socket 358. The rear portion of this socket 358 is extended forwardly at 340 and downwardly at 341 to form the top and tongue substantially similar to that illustrated in the modifications shown in Figs. 1 to 6 inclusive. In 35 addition, the tubular body 357 is extended upwardly and rearwardly from both sides of the extensions 356 and at 359 to form flaps which lie adjacent each other and reinforce the cap 34 so that the stem receiving 40 socket is substantially similar to that described in the prior patent referred to.

In Figs. 13, 14 and 15 the modified form of the invention is substantially similar to that disclosed in Figs. 5 and 8 for in these figures the bracket secures the socket 250 to the leg and said socket in turn suitably supports the caster stem. In this form, the socket 250 is provided with the head portion 50 251 and but one flange 253 is necessary and this is for limiting the inward movement of the socket. The base 430 is provided with the aperture 442 and in this aperture is positioned the socket 250. The base 430 is 55 provided with the usual projecting ledges 433 which in turn are provided with the forward up-turned flanges 444. The back 435 is provided with the side extension 436 in turn forming a portion of the groove, the 60 base of which is indicated by the numeral 437 and the front is indicated by 438. This groove has a wedging engagement as indicated at 439 of Fig. 13, with the angle iron leg. Herein the back 435, see Fig. 15, is 65 suitably slit at 445 to form the angularly extending and curved fingers 444 substantially similar to those described in Figs. 4 to 6 inclusive. These fingers frictionally engage the socket 250 and yieldingly retain the same upon the bracket when the socket 70 is removed from the caster stem. Inward movement of the socket, as previously described, is limited by the flange 253 engaging the base 430. The socket, therefore, is maintained in vertical alignment with respect to the base 430 by the fingers 444 and the back 445. If desired, the fingers may be shortened so that they are not interposed between the socket and the inner wall of the sides 20 of the angle iron and, then the 75 socket will lie directly against the angle iron.

In Figs. 16, 17 and 18 another modified form of the invention is illustrated, and in this form of the invention the socket 250 instead of being provided with two parallel flanges or enlargements 252 and 253, is provided with one flange enlargement and a pair of enlarged portions 254, substantially equivalent to the circular flange 252. With 80 these enlargements, however, the socket 250 is adapted to lie adjacent the inner angle walls of the side 20. In this form of the invention the back plate 535 extending upwardly from the base 530, and angularly 85 across the angle iron yieldingly forces the socket into engagement with said inner angle side wall by engaging the opposite and intermediate point of the socket. This form 90 of the bracket is provided with the usual forwardly supporting ledge 535 with the up-turned flange 534 and the back 535 is provided with the extension 536 which forms a portion of the groove, the base of which is indicated by the numeral 537 and the forward 95 portion of which is indicated by the numeral 538. This groove also has a wedging or clamping engagement, as indicated at 539. The base 530 is apertured at 542, and as shown in this form of the invention no 100 additional means is necessary to retain the socket in the bracket except the enlargements 253.

In Fig. 19 there is illustrated a further modified form of the invention and in this 105 form the bracket 635 extends from edge to edge of the angle iron leg 20 and the extension 637 with the inward extensions 638 form the clamping construction substantially similar to that shown in Figs. 7 to 9 inclusive. The bracket is provided with a top plate 640 and a bottom plate 630, which bottom plate is extended at 634 to form upwardly extending retaining members. In 110 Fig. 20 there is illustrated another modified form of the invention which is substantially similar to that disclosed in Figs. 13 to 15 inclusive. Herein the back 735 extends from edge to edge of the angle iron and the extensions 737 with the inward extensions 738 115

form the clamping construction. The base 730 supports the socket 742 and said base is further extended to provide the upwardly extending portions 734. The inwardly extending curved fingers 744 formed from the back 735 are adapted to frictionally retain the socket member 742. The foregoing construction is substantially similar to that particularly illustrated in Fig. 15.

In Fig. 21 a further modified form of the invention is illustrated which is substantially similar to that shown in Figs. 16 to 18 inclusive. In this form of the invention, the back 835 extends from edge to edge of the angle iron and the extensions 837 provided with further inwardly extending extensions 838 constitute the clamping construction. The base 830 is provided with an aperture to receive the socket member 250 for the enlargements 254 which rigidly secure said socket member to the base 830. The base 830 is also extended and is provided with the upwardly extending portions 834 substantially similar to the extensions 534 shown in the previously mentioned group of figures.

In the form shown in Figs. 7, 8, 9, 16, 17, 18, 19 and 21 the socket is shown rigidly secured to the bracket; in the form shown in Figs. 13, 14, 15 and 20 the socket is detachably supported by said bracket; and in the forms illustrated in Figs. 1 to 6 inclusive and 10, 11 and 12 the socket is formed integral with the bracket and may detachably but yieldingly support the caster stem. The caster socket 250, which is detachably or rigidly associated with the bracket as desired, supports the caster stem in any desired or preferred manner.

While the invention has been described in great detail in the foregoing specification, said detailed description is to be considered as illustrative and not restrictive in character for the same has been herein given for the purpose of providing a clear understanding of the invention, and the many modifications which will readily suggest themselves to those skilled in the art to which this invention applies, as well as the several modifications herein illustrated and described, are all considered to be within the broad purview of this invention as outlined by the appended claims.

The invention claimed is:

1. A caster socket bracket for an angular leg having a back portion extending from edge to edge of said leg, a clamping portion parallel to each edge and engaging the same, and a pair of fingers projecting from said back portion for clamping engagement within the angle formed by the angular leg.
2. A caster socket bracket for an angular leg having a back portion extending from edge to edge of said leg, a clamping portion inclined to the back portion and parallel to each edge and wedgingly engaging the same, a pair of fingers projecting outwardly from said back portion for clamping engagement within the angle formed by the angular leg, and supporting ledge means projecting forwardly from the lower part of said back portion.
3. In a device of the character described in claim 1, the addition of an outwardly extending base portion provided with an aperture therein adjacent the angle of the leg.
4. In a device of the character described in claim 2, the addition of an outwardly extending base portion provided with an aperture therein adjacent the angle of the leg.
5. In a device of the character described in claim 1, the addition of an outwardly projecting portion extending from the back portion and cooperating with the back portion to position a caster therein.
6. In a device of the character described in claim 2, the addition of an outwardly projecting portion extending from the back portion and cooperating with the back portion to position a caster therein.
7. In a device of the character described in claim 1, the addition of an outwardly projecting portion extending from the back portion and cooperating with the back portion to position a caster therein, and another outwardly extending portion provided with an aperture therein adjacent the angle of the leg, said aperture and said first mentioned projecting portion cooperating together for alignment purposes.
8. In a device of the character described in claim 2, the addition of an outwardly projecting portion extending from the back portion and cooperating with the back portion to position a caster therein, and another outwardly extending base portion provided with an aperture therein adjacent the angle of the legs, said aperture and said first mentioned projecting portion cooperating together for alignment purposes.
9. A caster socket bracket for an angular leg having a back portion extending from edge to edge of said leg, a clamping portion parallel to each edge and engaging the same, a pair of fingers projecting outwardly from said back portion for clamping engagement within the angle formed by the angular leg, and supporting ledge means projecting forwardly from the lower part of said back portion.
10. A caster socket bracket for an angular leg having a back portion extending from edge to edge of said leg, a clamping portion inclined to the back portion and parallel to each edge and wedgingly engaging the same, a pair of fingers projecting outwardly from said back portion for clamping engagement within the angle formed by the angular leg, and supporting ledge means projecting forwardly from the lower part of said back portion.
11. In a device of the character described in claim 1, the addition of an outwardly extending base portion provided with an aperture therein adjacent the angle of the leg.

in claim 9, the addition of upwardly projecting means upon said forwardly projecting support.

12. In a device of the character described in claim 9, the addition of upwardly projecting means upon said forwardly projecting support and inclined to form a clamp with the back portion.

13. In a device of the character described in claim 10, the addition of upwardly pro-

jecting means upon said forwardly projecting support and inclined to form a clamp with the back portion.

14. In a device of the character described in claim 10, the addition of upwardly projecting means upon said forwardly projecting support.

In witness whereof, I have hereunto affixed my signature.

WILLIAM H. NOELTING.
